RAPID SELECTOR MECHANISM

William E. Kierulff, Cincinnati, Ohio, assignor to
 The Crosley Radio Corporation, Cincinnati,
 Ohio, a corporation of Ohio

Application April 20, 1937, Serial No. 138,002

11 Claims. (Cl. 116—124.1)

My invention relates to means for facilitating the more rapid tuning of a radio set for example, to a predetermined station. It is useful in connection with those telephone dial like mechanisms which may be employed in connection with the usual dial of a radio set, and which have marked upon them pre-selected stations so that when the mechanism is swung around to bring the markings adjacent a marker or against a stop, 5 the station selected will be approximately in tune. Some of these mechanisms are quite elaborate and are designed to bring a pre-selected station exactly in tune without further attention on the part of the operator. I shall describe my invention however, in connection with a relatively simple mechanism, the purpose of which is to bring a pre-selected station approximately in tune, whereupon accurate tuning may be accomplished in another manner.

20 The problems with which my invention concerns itself are the problems of mounting, maintaining and operating a selector dial mechanism in an inexpensive but effective manner. Still other objects of my invention have to do with the elimination of rattling, the matter of smoothness of operation, and the matter of elimination 25 of parts heretofore thought necessary in the construction of simple or elaborate station selector mechanisms.

30 These and other objects of my invention which will be set forth hereinafter, or will be apparent to one skilled in the art upon reading these specifications, I accomplish by that certain construction and arrangement of parts of which I shall 35 now set forth the aforesaid exemplary embodiment.

Reference may now be made to the drawing, wherein:

Figure 1 is an elevational front view of the 40 assembled apparatus.

Fig. 2 is a central sectional view taken vertically along the line 2—2 of Fig. 1.

Fig. 3 is a horizontal sectional view taken along the lines 3—3 of Fig. 1.

45 Fig. 4 is a perspective view of the under side of a knob device which may be employed in connection with my structure.

Fig. 5 is a partial sectional view taken along the lines 5—5 in Fig. 1.

50 Fig. 6 is a perspective view of a marker device which may be employed in connection with the selector dial.

Briefly in the practice of my invention, I provide a main dial or plate and a cover glass of 55 arcuate or convex configuration. The cover glass

is perforated for the passage of the control shaft or concentric control shafts of the radio set, and the selector dialing mechanism is mounted in such a way that it is supported by and given a bearing upon the convex outer surface of the 5 cover glass. I shall use this terminology in describing my invention subsequently, although it will be understood that glass need not be the substance employed, and also that in some constructions particularly where the so-called cover glass is of opaque material and has on it the various scale markings, it may itself constitute the main dial of the radio set, and dial markings on the plate to the rear of it may be eliminated. The term plate as used in the claims will be 10 understood to include plates whether provided with dial indicia or not.

Moreover, I shall describe my invention in connection with the simplest form of control means where a hand knob is directly attached to the 20 selector dialing means and where this knob is in turn attached to the shaft of a gang condenser for example. It will be understood further, that more complicated constructions do not depart from the spirit of my invention. Thus the shaft 25 to which the aforesaid knob is attached, may be a hollow shaft and a second shaft may pass therethrough and bear a vernier tuning knob.

Still more complicated arrangements wherein there is a main tuning knob, a vernier tuning 30 knob, and a volume control, all on concentric shafts, will be within the skill of the worker in the art to construct in accordance with the teachings hereinafter contained, for the purpose of embodying in such structures the invention here- 35 in set forth.

In the particular embodiment which I shall disclose, a radio cabinet is indicated generally at 4. A radio chassis 6 is located behind a panel of the cabinet, and as shown supports a gang 40 condenser 7, having a shaft 8 and a dial or plate support 9. A dial or plate 10 is located in front of this support. Both the support and the dial or plate are perforated for the passage of the shaft 8. A convex cover glass 11 is held against 45 the dial by any suitable means, such for example as turned over portions 12 of the dial support. The cover glass 11 is also perforated to permit the passage of the shaft 8, and in the particular embodiment, to accept the shank of a tuning 50 knob hereinafter to be described.

I have indicated that the particular construction of the dial or plate is not a necessary limitation upon my invention. An effective construction is that set forth and claimed in the co-pend- 55

ing application of Leonard A. Kellogg, filed March 1, 1937, Serial No. 128,322, now issued as Patent 2,088,860, dated August 3, 1937. In accordance with that structure the member 10 may be made 5 of reflective substance, while the tuning indicia 13 may be placed on or etched into the cover glass 11. In order to prevent confusion of figures, an annular non-reflective member 14 may be placed over the member 10, directly beneath the dial 10 indicia. Elsewhere however, the member 10 gives 15 a reflected image of the indicia above it or any additional ornamentation, indicia or the like which may be placed upon the cover glass 11. There is an appropriate perforation 15 in the panel of the radio cabinet to permit visual access to the dial construction.

Referring particularly to Fig. 1, it will be seen that I have provided a selector dialing mechanism indicated generally at 16. It has an annular outer 20 portion 17, enlarged as at 18, upon one side at least, and provided with depressions 19, the shape of which will be most clearly appreciated from a consideration of Fig. 2. These depressions are 25 preferably of such size as to receive the finger tip for the purpose of rotating the selector dialing means. They may be so shaped as to receive markers 20 which may contain the call letters of desired stations. The selector dial is preferably made of relatively thin sheet metal. At its 30 outer edge it will usually have a down-turned stiffening flange 21, and at its inner edge it will likewise have a down-turned flange 22. This flange however is longer than the flange 21, and is adapted to extend from the general outer plane 35 of the annular member 17 back into contact with the convex surface of the cover glass 11.

The annular portion 17 is connected with a central boss or hub 23 by means of rib members 24, in the particular embodiment shown. Pointer 40 members 25 are also provided lying oppositely to the rib members 24. The central part of the hub 23 is died out in a non-circular shape (for instance hexagonal) as shown at 26, and at the corners of the died out figure enlarged cut-outs 27 45 are made. It will be seen that this leaves about the opening resilient tongues of metal.

The station selector dialing means is intended 50 for use with a knob, a convenient form of which is shown at 28. This has a body and a shank 29. The shank will be of the same shape as the non-circular cut-out 26 in the central hub of the selector dial, but will be of slightly larger outside dimensions. Thus if the dial is made of resilient 55 metal, and the shank 29 is pressed into the died out opening in the hub of the selector dialing means, the resilient tongues 26a on the selector dialing means will be slightly deflected and will grip tightly the shank 29 on the knob 28. This 60 relationship will be most clearly appreciated from a consideration of the cross sectional Figure 3. In this way the knob and the selector dialing means may be conveniently fastened together in a non-rotatable manner.

In the particular embodiment shown, the knob 65 28 has a central bore 30 to receive the shaft 8, and to which it may be non-rotatably fastened by means of one or more set screws 31.

As will be most clearly appreciated from Figures 70 2 and 3, the flange 22 on the selector dialing means touches and rides upon the convex surface 75 of the cover glass 11. Likewise the center boss or hub 23 rides upon this surface and the intervening parts, including the contacting portions of the pointer members 25 and the contacting 75 portions of the rib members 24 are so shaped as

to conform to and ride upon the surface of the cover glass.

The selector dialing means thus rides upon and is given a bearing upon the convex cover glass 11. It is supported thereby for smooth rotation and 5 is not subject either to displacement or to rattling during the operation of the radio set. Moreover any deflective forces applied by the finger of the operator are sustained by the cover glass without deflection of the selector dialing means. 10 The device is smooth in operation while simple and inexpensive to construct. Also the annular outer part of the station selector dialing means forms an ornamental edge finishing means or bezel for the cover glass 11, so that the hole 15 15 in the radio cabinet does not need to be finished in any particular way. It is obscured and covered by the selector dialing means. The mechanism may be arranged for edgewise or indirect illumination from the usual bulb 31. 20

In the operation of the device, markers for pre-selected stations are placed in those depressions 19 which correspond (if brought adjacent a suitable marker), to approximately tuned positions 25 for the stations in question. Thus when a rapid change of station is required, it is necessary for the operator only to place his finger tip in the depression marked for that particular station and swing it to the mark. In many instances no mark need be provided since it will be sufficient for the 30 operation of the device to swing the appropriate depression to the highest point of the mechanism. This results in bringing the station in question approximately into tune, but very much more rapidly than can be accomplished by the ordinary 35 operation of a dial mechanism. After the station has been brought approximately into tune, accurate tuning can be accomplished by manipulation of the knob 28. 40

As I have indicated, I have shown my device in its simplest form. No stops have been provided; but it will be understood that the principles of my invention as expressed in the appended claims, may be embodied in much more complicated structures, and in particular in structures 45 in which stops are provided and depressible plungers in the parts 19, which are adapted to be brought into alignment with the stops for accurate tuning. Likewise other modifications may 50 be made in my invention without departing from the spirit thereof.

Having thus described my invention, what I claim as new and desire to secure by Letters Patent is:

1. In a device of the character described, a 55 convex member, a shaft passing substantially centrally through said member, and a dialing mechanism mounted on said shaft and so shaped as to conform to the convex outer surface of said first mentioned member, whereby said first mentioned member forms a bearing for and gives support to said dialing member.

2. In a device of the character described, a 60 convex member, a shaft passing substantially centrally through said member, and a dialing mechanism mounted on said shaft and so shaped as to conform to the convex outer surface of said first mentioned member, whereby said first mentioned member forms a bearing for and gives support to said dialing member, said dialing member comprising a hub and an interspaced annular member connected with said hub by rib portions, 65 whereby said first mentioned member is visible 70 between said hub and said annular member.

3. In combination a selector dialing means 75

- comprising an annular outer member, an inner or hub member and connecting means, said annular member having an inner flange and said flange, said hub member and said connecting means having an inner configuration which is convex and is adapted to conform to and ride upon a convex supporting member of substantially the same circular area as the area of said dialing means.
10. 4. A station selector dialing means for a radio set comprising an annular outer member, an inner hub and connecting ribs, selector indicia in connection with said outer annular member, and a control knob non-rotatably attached to said hub, an inner flange on said outer annular member, and said flange, said ribs and said hub being so configured as to conform to and bear against a convex member having an area approximating the area of said selector dialing means.
15. 5. In a selector dialing means mechanism of sheet metal, an outer annular member, an inner hub member and connecting ribs, said inner hub member having a cut-out portion of non-circular shape with cut-outs intermediate parts thereof so as to leave resilient tongues in the metal, and a knob having a body, and a shank of the same configuration as said cut-out portions but of enlarged dimensions, whereby said hub may be pressed over said shank and said resilient 30 tongues of said hub will engage the sides of said shank to provide a substantially permanent non-rotative connection between said hub and said knob.
20. 6. In combination a plate, a convex cover glass for said plate, tuning mechanism having a shaft passing through perforations in said plate and in said cover glass, a station selector dialing means attached to said shaft and having a concave configuration whereby said selector dialing means may ride upon and be given bearing support by said cover glass.
25. 7. In combination a plate, a convex cover glass for said plate, tuning mechanism having a shaft passing through perforations in said plate and in said cover glass, a station selector dialing means attached to said shaft and having a concave configuration whereby said selector dialing means may ride upon and be given bearing support by said cover glass, pointer means on said station selector dialing means and indicia in connection with said plate and said cover glass and visible through the latter.
30. 8. In a radio set, a radio chassis having a tuning shaft, a radio cabinet having a perforation therein, a perforated convex member through which said shaft passes and mounted in connection with the perforation in said cabinet, and a station selector dialing means mounted on said shaft and having an under surface conforming to and riding upon said convex member, said dialing means having an annular projection adapted to extend over and conceal the edges of said perforation in said cabinet.
35. 9. In a radio set, a radio chassis having a tuning shaft, a radio cabinet having a perforation therein, a perforated convex member through which said shaft passes and mounted in connection with the perforation in said cabinet, and a station selector dialing means mounted on said shaft and having an under surface conforming to and riding upon said convex member, said dialing means comprising an outer annular portion having an inner flange adapted to rest upon said convex member, an inner hub resting upon said convex member and ribs connecting said hub with said outer annular member, said ribs also shaped to rest upon said convex member, said ribs also shaped to rest upon said convex member.
40. 10. In a radio set, a radio chassis having a tuning shaft, a radio cabinet having a perforation therein, a perforated convex member through which said shaft passes and mounted in connection with the perforation in said cabinet, and a station selector dialing means mounted on said shaft and having an under surface conforming to and riding upon said convex member, said dialing means having an annular projection adapted to extend over and conceal the edges of said perforation in said cabinet, said dialing means comprising an outer annular portion having an inner flange adapted to rest upon said convex member, an inner hub resting upon said convex member and ribs connecting said hub with said outer annular member, said ribs also shaped to rest upon said convex member, said ribs also shaped to rest upon said convex member.
45. 11. In a radio set, a radio chassis having a tuning shaft, a radio cabinet having a perforation therein, a perforated convex member through which said shaft passes and mounted in connection with the perforation in said cabinet, and a station selector dialing means mounted on said shaft and having an under surface conforming to and riding upon said convex member, said dialing means having an annular projection adapted to extend over and conceal the edges of said perforation in said cabinet, said dialing means comprising an outer annular portion having an inner flange adapted to rest upon said convex member, an inner hub resting upon said convex member and ribs connecting said hub with said outer annular member, said ribs also shaped to rest upon said convex member, knob means non-rotatably attached to said selector dialing means and forming the means for connecting said selector dialing means to said shaft.
50. 12. In a radio set, a radio chassis having a tuning shaft, a radio cabinet having a perforation therein, a perforated convex member through which said shaft passes and mounted in connection with the perforation in said cabinet, and a station selector dialing means mounted on said shaft and having an under surface conforming to and riding upon said convex member, said dialing means having an annular projection adapted to extend over and conceal the edges of said perforation in said cabinet, said dialing means comprising an outer annular portion having an inner flange adapted to rest upon said convex member, an inner hub resting upon said convex member and ribs connecting said hub with said outer annular member, said ribs also shaped to rest upon said convex member, knob means non-rotatably attached to said selector dialing means and forming the means for connecting said selector dialing means to said shaft, and pointer means in connection with said selector dialing means attached to said hub.

WILLIAM E. KIERULFF.
